United States Patent Office.

EDWIN STAFFORD, OF PHILADELPHIA, PENNSYLVANIA.

Letters Patent No. 68,464, dated September 3, 1867.

IMPROVEMENT IN OPERATING CONDENSING-ROLLERS IN CARDING MACHINES.

The Schedule referred to in these Letters Patent and making part of the same.

TO ALL WHOM IT MAY CONCERN:

Be it known that I, EDWIN STAFFORD, of Manayunk, city and county of Philadelphia, and State of Pennsylvania, have invented a certain new and useful Improvement in Rubber Motion for Carding Engines; and I do hereby declare that the following is a full, clear, and exact description of the construction and operation of the same, reference being had to the annexed drawings, making a part of this specification, in which—

Figure 1 is a top view.

Figure 2 is a side view.

Figure 3 is an end view.

Other drawings are in detail, similar letters in the drawing representing the same parts.

The nature of my invention consists in giving to rubber rollers of condenser carding engines a double reciprocating longitudinal motion. The object accomplished is presenting all the surface of the rubber rollers to the action of the slubbing or sliver during the process of rubbing, preventing thereby ridges and hollows on the surface of the rollers, which is a source of great trouble, particularly in working coarse or short-fibred material, which requires quick, short strokes of the rubbers to prepare the slubbing properly for spinning. With my improvement, a short or long stroke can be had at pleasure, and the same time a continuous changing of the relative position of the rubber rollers to the doffers to accomplish the said object.

To enable others to make and operate my improvement, I will proceed to describe the construction and operation of it, reference being had to the drawings.

Letter A is a frame of a rubber motion as in ordinary use. To this frame are fitted guides for cross-heads to work in, to which cross-heads are attached roller-shafts. These cross-heads are also connected to eccentrics on the shaft M by means of straps, the whole of said guides, cross-heads, and eccentrics being constructed in the ordinary way. Letter M is an eccentric shaft, fitted to cross-heads or slides, letter D, working on guides C C, which guides are fastened to the stands B B, which stands are fastened to the frame A. Letter L is an upright shaft, on which are attached eccentrics E' E'. The top eccentric is connected to the cross-head by means of a strap, N. The lower eccentric is connected to the shaft M by means of the strap O. Letter H is a shaft, (at right angles to shaft L), on one end of which is a worm, driving the shaft L by means of worm-wheel F. On the other end is a pulley. Letter K is a shaft, at right angles to an upright shaft M, which shafts are geared to each other by bevel-wheels. The shaft K is held in place by a hanger-box, P, which is attached to the lower slide D. The shaft K has a shoulder fitting on each side of the box P, which causes said shaft to travel with the slide D.

The operation of my invention is as follows: Motion being given to the shaft K, gives to the rubber rollers a reciprocating motion in the usual manner, by means of the eccentrics on the shaft M. The pulley on the shaft H receives motion from one of the doffer shafts. The shaft H and L, being geared by means of the worm and worm-wheel F, as described, gives the shaft L a slow motion, and it, by means of the eccentrics attached thereto, gives to the shaft M a reciprocating motion in addition to the rotary motion given by the shaft K, thereby giving a double reciprocating motion to the rubbers, one being quick, the other motion slow. The eccentrics E E are adjustable, to give sufficient throw to accomplish said object, namely, the prevention of ridges and hollows on the surface of the rollers.

I have described but one method of actuating shaft M, but this motion may be imparted by other mechanical contrivances, viz, a crank, or a right and left screw, or any appliance that will give a reciprocating motion to the shaft M.

Claim.

I claim giving to the rubber or condensing-rollers of a carding machine a double reciprocating motion, substantially as and for the purpose described.

EDWIN STAFFORD.
